MEANS FOR TREATING WEB MATERIALS

Wistar Wright Macomson, Charlotte, N.C., assignor to Paterx Corporation, Charlotte, N.C., a corporation of North Carolina

Application May 9, 1957, Serial No. 658,152

16 Claims. (Cl. 68—3)

This invention relates to an improved apparatus for and process of treating web materials of any type which are capable of penetration by fluid in liquid or gaseous form and including materials such as parallel textile strands, cloth, felt, sheet paper pulp and the like.

It is an object of this invention to provide a novel process of and means for agitating or vibrating fluids to facilitate rapid penetration of pervious web materials during continuous movement thereof through a fluid.

It is another object of this invention to provide a process of treating pervious web materials comprising passing a web through a fluid (liquid or gas) and while passing the web through a zone or zones of agitation while confining the fluid to the extent that the waves of agitation are of substantially uniform force throughout the lateral thickness or depth of the fluid and while causing the waves of agitation to impinge upon the entire width of the web in said zones or zone.

It is another object of this invention to provide a process of the character last described wherein the frequency of the waves of agitation or vibration of the fluid is effected at either sonic or ultrasonic frequencies; that is, at from five cycles per second to sixty thousand cycles per second.

It is still another object of this invention to provide a process of the character described in which the direction of the vibrations in adjacent zones are opposite from each other.

It is another object of this invention to provide apparatus for carrying out the process above described comprising a chamber for containing a fluid through which the web material passes and wherein at least one of the opposed walls of the fluid chamber is provided with means for creating vibrations to thereby agitate the fluid in a zone, or a plurality of successive zones, which preferably encompass the entire width of the web material, and wherein said opposed walls are spaced from each other a distance substantially the same as or less than the distance throughout which the vibrations are substantially uniformly imparted to the fluid.

It is another object of this invention to provide apparatus for the fluid treatment of web material comprising a chamber including opposed walls which are spaced relatively close together and between which the web material passes and wherein at least one of said opposed walls is provided with means for agitating the fluid therein throughout at least the width of the web material at a frequency of from five cycles per second to sixty-thousand cycles per second.

It is another object of this invention to provide apparatus of the character described wherein, in one embodiment, at least one of the said walls of the chamber is made from a pliable or resilient material and is provided with one or more transversely extending and relatively narrow bars, plates or other rigid members with means for imparting movement to the rigid members inwardly and outwardly at predetermined frequency to

2

correspondingly agitate the fluid through which the web material is passed.

It is still another object of this invention to provide apparatus of the character last described including a plurality of said rigid members and wherein alternate or adjacent members move in the opposite direction from adjacent or intervening rigid members with each movement during reciprocation thereof.

It is still another object of this invention to provide another embodiment of apparatus of the character described wherein opposed walls, between which the web passes, are made from a substantially rigid material and at least one of the walls has one or more rows of transducers thereon disposed in close relative proximity. The transducers are preferably arranged in at least one pair of adjacent rows with those in one row being spaced in alternation to the transducers in the other row. Said transducers are capable of setting up ultrasonic waves in the fluid, which waves vibrate through a rapid succession of changes in dimension and transmit the vibrations as pressure waves to the fluid through which the web passes, said transducers being capable of vibrating the fluid at a rate of from twenty-thousand to sixty-thousand cycles per second.

Some of the objects of the invention having been stated, other objects will appear as the description proceeds when taken in connection with the accompanying drawings, in which—

Figure 1 is a side elevation of one form of apparatus for carrying out the improved process;

Figure 2 is a plan view of the apparatus shown in Figure 1 taken substantially along line 2—2;

Figure 3 is a fragmentary vertical sectional view, partially broken away, taken substantially along line 3—3 in Figure 1;

Figure 4 is an enlarged vertical sectional view, longitudinally of the direction of movement of the web taken substantially along line 4—4 in Figure 1, and showing, somewhat schematically, some of the associated elements;

Figure 5 is an elevation looking at the right-hand side of Figure 1;

Figure 6 is a side elevation of a modified form of apparatus in which transducers are used, whereas the apparatus shown in Figures 1 through 5 is provided with rigid members for effecting vibrations to the fluid through which the web passes;

Figure 7 is an elevation looking at the right-hand side of Figure 6;

Figure 8 is a sectional plan view taken substantially along line 8—8 in Figure 7;

Figure 9 is an enlarged vertical sectional view, with parts shown somewhat schematically, taken substantially along line 9—9 in Figure 7.

In the processing of web material such as dyeing, washing, sizing, desizing and mercerizing of textile materials, applying plastic to pervious web materials, drying pulp in sheet form and in treating other materials, I have discovered that such web materials may be processed at a very rapid speed as compared to prior processes by vibrating the fluid through which the material is passed for treating the same. Some attempts have been made in the processing of web material to utilize subsonic vibrations with movement of fabric through a liquid bath for dimensionally stabilizing the fabric. An example of this type of treatment is disclosed in United States Patent No. 2,699,592, dated January 18, 1955, and issued to James A. Newnam. The use of vibrating diaphragms for creating vibrational waves in clothes washing machines is also disclosed in various United States patents, such as Nos. 2,076,011; 2,555,464; 2,623,376 and others.

Now, I have discovered that the speed at which a continuous moving pervious web material can be efficiently

processed during penetration of the web material by a fluid, in either gaseous or liquid form, is greatly increased as compared to prior processes, by creating vibrational waves in the fluid with which the web material is penetrated in a zone or successive zones which preferably encompass the entire width of the previous material being processed and wherein the vibrational waves are effected in either sonic or ultrasonic frequencies or, in other words, at a frequency of from five cycles per second to sixty-thousand cycles per second.

One form of novel apparatus for processing web materials according to the present invention is illustrated in Figures 1 through 5, this form being so constructed as to produce sonic vibrations of from approximately five cycles per second to approximately two-hundred-fifty cycles per second in a given zone or zones through which the material passes. A modified form of novel apparatus for processing web material according to the present invention is illustrated in Figures 6 through 9, this apparatus being so constructed as to create ultrasonic vibrations in the fluid at a frequency of from approximately twenty-thousand cycles per second to approximately sixty-thousand cycles per second in a given zone or zones through which the web material passes. The first form of the apparatus shown in Figures 1 through 5 will now be described.

Referring particularly to Figures 1 through 5, the numeral 10 broadly designates a main fluid treatment chamber adapted to contain a treating fluid F. Various types of fluid may be used as will be described hereinafter. The main fluid treatment chamber is broadly characterized by relatively closely spaced walls containing the treating fluid, and between which a web material W is passed, the walls preferably being spaced from one to six inches apart, by way of example, so that the vibrational waves created by sources at either of the walls will not have diminished materially by the time they have reached the opposite or other wall, thus insuring thorough agitation of the fluid throughout its thickness or expanse between the walls.

Although not limited thereto, the main chamber 10 is shown in Figure 4, as being of generally U-shaped construction and includes a substantially semi-circular or arcuate bottom wall 11, a pair of opposed outer side walls, 12, 12' and opposed end walls 13, 13'. Inner side walls 14, 14' are spaced inwardly from and extend between the respective outer side walls 12, 12' and define an auxiliary temperature controlling chamber (heating or cooling chamber) 15 therebetween, the temperature controlling chamber 15 being closed at its lower end by a plate 16 spaced above the bottom of the main chamber 10. Since the main chamber 10 is substantially U-shaped, the two legs thereof actually embody sub-chambers or compartments A, B. Since it may be necessary to remove the temperature controlling chamber 15 from within the main chamber 10 for the purpose of threading web material W through the main chamber, opposite ends of the temperature controlling chamber are also closed by end plates 17, 17' positioned closely adjacent the respective end walls 13, 13' of the main chamber 10. The plate 16 extends between and is connected to the inner wall members 14, 14' and the end plates 17, 17'.

The main chamber 10 is carried by a frame 20 comprising a pair of opposed inverted substantially U-shaped end frame members 21, 21' which are spanned by respective vertically spaced intermediate and substantially horizontally disposed frame members 22, 23 and 22', 23'. The end wall 13 is suitably secured to the upper horizontal portion of the end frame member 21 and the intermediate horizontal frame members 22, 23 extending between the vertical legs of the inverted U-shaped frame member 21. The end wall 13' is suitably secured to the upper portion of the inverted U-shaped end frame members 21' and the corresponding intermediate horizontal frame members 22', 23' extending between the vertical legs of the inverted U-shaped frame member 21'.

A pair of vertically spaced front transverse frame members 24, 25 extends between and is suitably secured to the front legs of the inverted U-shaped frame members 21, 21', and a similar pair of vertically spaced transverse frame members 24', 25' extends between and is suitably secured to the rear legs of the inverted U-shaped frame members 21, 21' (Figures 1, 2, 3 and 4).

The front and rear walls 12, 12' of the U-shaped chamber 10 are, for the most part, made from a pliable or resilient leak-proof sheet material such as rubber, synthetic rubber (neoprene), plastic or the like, and are supported by and extend between respective substantially rectangular frames 30, 30' which are preferably made from angle plates or angle bars as best shown in Figures 3 and 4. The curved bottom wall 11 of the chamber 10 may be provided with front and rear outwardly projecting flanges 31, 31' suitably secured to the lower portions of the respective rectangular pliable wall-supporting frames 30, 30'. Suitable gaskets 32 may be provided between the flanges 31, 31' and the lower substantially horizontal portions of the respective rectangular frames 30, 30'.

The upper substantially horizontal portions of the rectangular frames 30, 30' are suitably secured to the bottom wall members 34, 34' of respective sealing chambers 35, 35' whose inner or proximal walls 36, 36' serve as extensions to the upper ends of the respective walls 12, 12', but which terminate on a lower level than the upper ends of the temperature-controlling chamber walls or inner walls 14, 14'. It should be noted that the upper portions of the end walls 13, 13' are somewhat wider than their lower portions; that is, the end walls 13, 13' are substantially T-shaped, to accommodate the sealing chambers 35, 35' and serve as end walls to the sealing chambers.

The sealing chambers 35, 35' are also provided with respective front and rear walls 37, 37' whose upper ends terminate on a substantially higher level than the upper edges of the inner or proximal walls 36, 36' of the sealing chambers 35, 35'. The lower portions of vertically disposed baffle plates 40, 40' terminate in spaced relationship above the bottoms 34, 34' of the sealing chambers 35, 35' and extend upwardly therefrom and preferably terminate above the level of the upper edges of the respective front and rear walls 37, 37'. Medial portions of the baffle plates 40, 40' have respective rests or projections 41, 41' thereon upon which front and rear edges of a cover plate or platform 42 normally rest.

The upper edges of the inner walls 14, 14', which define the temperature control chamber 15 therebetween, along with the end walls 17, 17', are connected to or suspended from the cover plate 42. The cover plate 42 preferably has a pair of spaced loop members or handles 43, 43' thereon which may be engaged by a suitable lift mechanism, not shown, for raising the temperature controlling chamber 10 and to facilitate the threading of the web material W therethrough.

The cover plate 42 is spaced above the upper edges of the inner walls 36, 36' of the respective sealing chambers 35, 35' to permit the web material W to pass therebetween. Suitable seals or gaskets 45, 45' may be provided between the bottom walls 34, 34' of the sealing chambers 35, 35' and the upper substantially horizontal members of the respective pliable-wall-supporting frames 30, 30'.

The web material W may be drawn from a suitable source, not shown, between a pair of upper and lower driven feed rolls 50, 51. The web material then passes over an idler roll 52 and then downwardly partially around and beneath a pair of idler rolls 53, 54, then upwardly over another pair of idler rolls 55, 56, and then downwardly through the rear portion or compartment of the chamber 10; that is, between the walls 12', 14'. During its passage through the chamber 10, the web material W passes through a suitable treating fluid F.

The lower portion of the main chamber 10 has a relatively large idler roll 57 therein which is sufficiently large so that opposite vertical runs of the web material W may pass through the treating fluid while being maintained in spaced relation to the inner walls 14, 14' defining the temperature controlling chamber 15 therebetween. The web material passes upwardly from the idler roll 57 and over a pair of relatively small idler rolls 60, 61, then downwardly beneath a pair of idler rolls 62, 63, while also passing beneath the lower edge of the baffle plate 40. The web material then passes upwardly from the idler roll 63 and over an idler roll 64 and is withdrawn between a pair of driven upper and lower rolls 65, 66 which are preferably covered with a resilient material to serve as squeeze rolls. The feed rolls 50, 51 are also preferably covered with a resilient material.

The idler rolls 52 through 57 and 60 through 64 may be suitably journaled in the opposed end walls 13, 13' of the main chamber 10. Opposite ends of the front and rear bottom driven rolls 66, 51 are journaled in respective pairs of bearing stands 70, 70' and 71, 71' (Figures 1, 2, 4 and 5). To facilitate removal of the top rolls 50, 65, the bearing stands 70, 71, 70', 71' are provided with respective slots or notches 72 in their upper ends in which corresponding reduced ends of the corresponding rolls 50, 65 are loosely mounted for rotation therein.

It is important that the feed of the web material W through the main chamber 10 be carefully regulated to insure that the web material passes through the fluid F at the desired speed and to also insure that the web material is maintained under the proper tension. Therefore, it will be observed in Figures 1, 2 and 5 that a separate variable-speed drive unit is provided for each of the sets of rolls 50, 51 and 65, 66. The variable-speed drive units are shown somewhat schematically, since there are many different types of variable-speed units which will serve the intended purpose and, accordingly, a detailed description thereof is deemed unnecessary.

The variable-speed drive units for the set of web withdrawing or squeeze rolls 65, 66 and the set of feed rolls 50, 51 are respectively designated at 75, 75' in Figures 1, 2 and 5. Each of the variable-speed drive units is provided with a suitable control 76 for controlling the output speed of the corresponding variable-speed drive unit. The variable-speed drive units 75, 75' drive respective pulleys 81, 81' fixed on corresponding reduced ends of the respective rolls 66, 51.

The variable-speed drive units 75, 75' may be suitably secured to the upper portion of the inverted U-shaped frame member 21. It will be observed in Figures 1, 2 and 5 that corresponding reduced ends of the bottom rolls 51, 66 each has a gear 83 fixed thereon which meshes with a gear 84. The gears 84 are fixed on the corresponding reduced ends of the respective top rolls 50, 65. Since the rolls 65, 66 may serve as squeeze rolls, a suitable pan 85 may be provided beneath the lower squeeze roll 66 to direct any excess fluid back into the corresponding sealing chamber 35 through an opening 86 provided in the front wall 37 of the front sealing chamber 35.

The treating fluid may be fed into the main chamber 10 by any suitable means and, in the embodiment shown schematically in Figure 4, a means is provided for feeding the fluid from a fluid source 90 into either one or both of the sealing chambers 35, 35' and/or directly into the main chamber 10. Of course, when the treating fluid is fed into the sealing chambers 35, 35', it may be caused to flow over the upper edges of the inner walls 36, 36' of the respective sealing chambers 35, 35' and, thus, into the main chamber 10.

To this end, it will be observed schematically in Figure 4 that the fluid source 90 has a pipe-line or conduit 91 leading therefrom in which a suitable pump 92 is interposed. The pipe-line 91 extends upwardly in the

left-hand portion of Figure 4 and then inwardly and is communicatively connected to the sealing chamber 35'. A medial portion of the conduit or pipe-line 91 has a branch pipe or conduit 93 leading therefrom which 5 communicates with the liquid sealing chamber 35, preferably through the front wall 37 thereof.

The conduit 91 has a suitable manually or automatically operable valve 94 interposed therein between the point at which a branch pipe 97 is connected thereto and the sealing chamber 35'. The branch conduit 93 also has a similar valve 95 interposed therein. The branch pipe or conduit 97 leads from pipe 91 to the main fluid chamber 10 and is preferably connected to end wall 13. A valve 98 is interposed in pipe 97. Thus, it is 15 apparent that the fluid may be pumped into the chambers 35, 35' and/or the main chamber 10.

A suitable fluid level control means, shown schematically at 96, may be provided in the main chamber 10 for closing the corresponding valve 94 or 95 automatically upon the level of the fluid in the chamber, if in liquid form, reaching a predetermined maximum. Level controlling devices such as may be used to serve the purpose of the device 96 are well-known in the liquid treatment of web materials and a detailed illustration and 20 description thereof is thus deemed unnecessary. For example, a suitable liquid level control apparatus is disclosed in United States Patent No. 1,978,536, dated October 30, 1934.

In order that the fluid may be continuously circulated 30 through the main chamber 10, a return pipeline or conduit 99 is connected to a lower portion of the main chamber 10 at one end thereof and leads to the fluid source 90. A suitable drain, embodied in a valve 100, is preferably provided at the lowermost portion of the 35 arcuate bottom wall 11 of the main chamber 10 for draining the contents of the main chamber 10 for cleaning or other purposes, when desired.

The temperature controlling chamber 15 may be maintained at the desired temperature, depending upon the 40 character of the fluid and/or web material W being processed, by any suitable means. An example of such means is illustrated schematically in Figure 4 wherein it will be observed that pipe-lines or conduits 110, 111 are detachably connected to the end wall 13 and end wall 45 17 for communication with the upper and lower portions, respectively, of the temperature controlling chamber 15. Corresponding ends of the pipe-lines 110, 111 are connected to opposed portions of a temperature determining means shown schematically at 112 in Figure 4. The temperature determining means may be in the form of a heating device, a boiler for hot water or for forming steam, a refrigerator or merely a source of cold or hot water, depending upon the temperature desired to be maintained in the temperature controlling chamber 15 and, in turn, the temperature at which the fluid is to be 55 maintained.

Suitable valves 113, 114 may be provided in the respective pipe-lines 110, 111 for controlling or stopping the flow of fluid therethrough. Although a fluid-type 60 of temperature regulating means is described herein, it is to be understood that the fluid in the main chamber 10 may be maintained at a relatively high temperature by electrical or other means, without departing from the spirit of the invention.

Means are provided for vibrating or agitating the fluid in opposed front and rear portions of the main chamber, in zones which preferably extend throughout the width of the fabric or other web material being processed, to thereby insure rapid and thorough penetration of the web material by the fluid through which it passes. A plurality of such zones is provided in each of the front and rear portions or compartments of the main chamber 10, the resilient or pliable front and rear walls 12, 12' of the main chamber 10 being provided

for the specific purpose of facilitating the agitation or vibration of the fluid.

To this end, it will be observed in Figures 1, 3 and 4 that the inner or rear surfaces of the front pliable wall 12 of the U-shaped chamber 10 has a plurality of vertically spaced substantially horizontally disposed plates, bars or rigid members attached thereto, there being four such rigid members indicated at 121 through 124 in Figure 4. A similar series of such rigid members, plates or bars is provided on the inner or front surface of the rear pliable wall 12', and these rigid members are indicated at 121' through 124'.

The rigid members 121 through 124 and 121' through 124' preferably extend throughout at least the entire width of the plane of the path of travel of the web material W. These rigid members 121 through 124 and 121' through 124' are fastened to the inner surfaces of the respective pliable walls 12, 12' and, preferably, the fastening means therefor extends through the corresponding pliable wall and is attached to a corresponding outer rigid member, which is shown in the form of a channel bar. The channel bars corresponding to the respective inner rigid members 121 through 124 and 121' through 124' are respectively designated at 125 through 128 and 125' through 128'.

The bars 125 through 128 and 125' through 128' are preferably of substantially the same length as the respective inner bars or rigid members 121 through 124 and 121' through 124'. Each of the bars 125 through 128 has corresponding ends of a pair of connecting rods or links 131, 132 pivotally connected thereto and each of the outer bars 125' through 128' also has corresponding ends of a pair of connecting rods or links 131', 132', pivotally connected thereto (Figures 3 and 4). The links or connecting rods 131, 132, 131', 132' are caused to reciprocate at sonic speed by respective cams 133, 134, 133', 134'. The latter cams may impart reciprocatory movement to the corresponding connecting rods in any desired manner.

In this instance, it will be observed in Figure 3 that the cams 133, 134, 133', 134' are eccentrically secured on respective upright shafts 135, 136, 135', 136' and enlarged outer ends of the corresponding connecting rods 131, 132, 131', 132' loosely fit around or encircle the respective cams 133, 134, 133', 134' whereby rotation of the latter cams imparts inward and outward reciprocatory motion to the rigid members 121 through 124 and 121' through 124'. It should be noted that the cams 133, 134, 133', 134' in the ends of the connecting rods associated with the bars 125, 127, 125', 127' face in substantially opposite directions from cams associated with the intervening or other bars 126, 128, 126', 128' so that, as the bars 122, 122' and 124, 124' move outwardly with each reciprocation thereof, the rigid members or bars 121, 121' and 123, 123' move inwardly, and vice versa, so the waves or vibrations effected by adjacent rigid members move relatively in opposite directions.

Although the means for creating the waves or vibrations are illustrated herein as provided in the outer walls 12, 12' of the main chamber 10, it is apparent that similar means may be provided in the immediately opposite or inner walls 14, 14' respectively, without departing from the spirit of the invention.

The shafts 135, 136, 135', 136' may be driven to rotate at the desired speed by any suitable means and it is preferable that the shafts 135, 136 are driven at substantially the same speed as the shafts 135', 136', although this may not be absolutely necessary. The front cam shafts 135, 136 are each journaled in a pair of vertically spaced bearing members 140, 141. The rear cam shafts are each journaled in a pair of vertically spaced bearing members 140', 141'. The bearing members 140, 141, 140', 141' are each preferably in the form of pillow blocks of the usual type having wide-inner-race anti-friction bearings therein so the inner races of the

bearing may be secured to the corresponding shafts to maintain the shafts in the desired positions.

The bearing members 140, 141 are suitably secured to the inner or rear surfaces of the respective transverse frame members 24, 25 of the frame 20 and the bearing members 140', 141' are suitably secured to the respective upper and lower rear transverse frame members 24', 25'. The lower ends of the cam shafts 135, 136 each has a bevel gear 142 fixed thereon and the lower ends of the cam shafts 135', 136' each has a bevel gear 142' fixed thereon.

The bevel gears 142 each mesh with a corresponding bevel gear 144 and the bevel gears 142' each mesh with a bevel gear 144' (Figures 1 and 4). The bevel gears 144 are fixed on a common substantially horizontally disposed shaft 145 at the front of the apparatus and the bevel gears 144' are mounted on a common substantially horizontally disposed rear shaft 145'. The shafts 145, 145' are journaled in respective bearing members or blocks 146, 147 and 146', 147', the bearing blocks 146, 147 being carried by the front legs of the inverted U-shaped frame members 21, 21' and the bearing blocks 146', 147' being carried by the rear legs of the respective inverted U-shaped frame members 21, 21'.

Referring to Figures 1, 3 and 5, corresponding ends of the front and rear shafts 145, 145' are suitably coupled together by means of sprocket wheels 150, 150' fixed on the respective shafts 145, 145', and over which an endless sprocket chain 151 is entrained. The front shaft 145 is coupled, by means of a shaft coupling or clutch 152, to an output shaft 153 of a gear-reduction unit 154 containing suitable gearing, not shown, for transmitting rotation from an input shaft 155 to the output shaft 153 and whereby the output shaft 153 may rotate at a substantially greater speed than the input shaft 155.

The input shaft 155 has a V-pulley 156 fixed thereon about which a V-belt 157 is entrained. The V-belt 157 is also entrained over an expansible or variable-speed pulley 160 driven by a suitable prime mover 161 shown in the form of an electric motor in Figures 3 and 5. The electric motor is fixed on a motor support 162 having downwardly projecting ears 163 thereon guided for longitudinal movement on guide bars or rods 164.

Opposite ends of the guide rods 164 are fixed in suitable standards or frame members 164 fixed upon the floor upon which the main frame 20 rests. The central lower portion of the motor support 162 has an adjustment shaft or screw 166 threaded therethrough whose opposite ends are journaled in the frame members 164 and one end of which has a hand-wheel 167 fixed thereon for adjusting the motor 161 toward and away from the gear-reduction unit 154 to correspondingly vary the speed of the gear-reduction unit. The gear-reduction unit 154 is fixed on a suitable stand 170 which is also suitably secured to the floor upon which the main frame 20 rests.

It is thus seen that means are provided for feeding the web material W into and withdrawing the web material W from the main chamber 10 at predetermined speed while maintaining predetermined tension in the web material and while maintaining the fluid under pressure therein, wherein the web material is so guided through the fluid in the chamber as to be positioned in the desired proximity to the pliable walls or the zones in which the vibrations are created and, also, so the web material is maintained out of contact with either of opposed walls of each of the compartments defined between the walls 12, 14 and 12', 14'. It is apparent that rotation of the cam shafts 135, 136, 135', 136' imparts reciprocatory in-and-out motion to the vibrating elements or rigid members 121 through 124 and 121' through 124' at predetermined speeds to thereby form zones of vibrational waves of predetermined frequency and wherein the vibrations created in the fluid F are relatively opposite with respect to the direction thereof with reciprocation of adjacent rigid vibrating elements.

Due to the mechanical elements involved in the form of apparatus heretofore described and illustrated in Figures 1 through 5, the extent of the frequency of the vibrational waves which are created by the reciprocating vibrating elements or rigid members 121 through 124 and 121' through 124' should be limited to some extent, and it has been found desirable to drive the cam shafts 135, 136, 135', 136' so as to create vibrational waves in the fluid F of from five cycles per second to no more than two-hundred-fifty cycles per second, a range of from sixty cycles per second to one-hundred-twenty cycles per second being preferred.

In impregnating woven or knit cloth or other textile materials in web form, while continuously moving the same under predeterminedly controlled tension through a pressurized dye liquor in the main chamber 10, it has been found that the creation of vibrational waves in the dye liquor increases the speed at which the fabric or web material may be passed through the dye liquor, as represented by the fluid F, as much as ninety percent greater than has been possible heretofore. For example, whereas normal dyeing processes would require one hour in order to dye a given length of fabric, the present process, utilizing apparatus of substantially the character disclosed in Figures 1 through 5, requires approximately six minutes in order to dye said given length of web material, the latter process being carried out while creating sonic vibrational waves in the bath of from sixty cycles per second to one-hundred-twenty cycles per second.

In order to further insure that the web material W is maintained out of engagement with either of the walls of each compartment of the main chamber 10, a series of staggered guide rods may be provided in each of the opposed compartments, A, B, between which the web passes, the guide rods in the front portion or compartment A of the main chamber 10 being indicated at 175 and the guide rods in the rear compartment B of the main chamber 10 being indicated at 175'. These guide rods may be suitably attached at opposite ends thereof to the end walls 13, 13' and may remain stationary or may be in the form of idler rolls as desired.

The guide rods 175, 175' may be desired, due to the distance between the two walls of each compartment of the main chamber 10 since, as heretofore stated, the walls 12, 14 and 12', 14' are preferably spaced from one inch to six inches apart to insure that the vibrational waves do not materially diminish from the point at which they are created before having agitated the full thickness or expanse of the fluid between the adjacent walls. Also, in the lower sonic frequencies, the vibrational waves are necessarily relatively large and diminish in size, but increase in intensity or force, as they increase in frequency. Thus, the larger vibrational waves effected at low frequencies may tend to move the cloth or other pervious web material at the particular zones in which they are present to the extent that, if the guide rods 175, 175' were not provided, the web material might be thrown against the opposite wall of the corresponding compartment.

Earlier in this context, an example of the process of the present invention has been given as applied to the dyeing of textile web material in a dye liquor. However, the principles of the present process are also equally applicable in instances wherein the fluid may be of gaseous form, such as hot air, for the drying of various types of web materials such as sheet paper pulp. The process is also applicable to apply a plastic material to a pervious web material; the sizing, washing, scouring or drying of textile web materials or to the application of caustic materials to textile web materials for mercerizing, or for desizing textile web materials to break down the starch in the textile web material. In other words, in a broad sense, the present method is applicable to the treating of any type of web material capable of penetration by moisture or gas.

Although the apparatus shown in Figures 1 through 5 has been described as having a plurality of zones in which vibrational waves are created in the fluid, it is apparent that there may be instances in which only a single zone of this character need be provided. Also, liquid F in the sealing chambers 35, 35' serves as a liquid seal to maintain pressure in the main chamber 10. However, it should be understood that other sealing means may be used in processing with a gaseous fluid in the main chamber, such as hot or cold air.

Modified form of web treating apparatus

As heretofore stated, the form of apparatus illustrated in Figures 1 through 5 is limited, in the creation of vibrational waves in the treating fluid, to sonic frequencies which preferably do not exceed two-hundred-fifty cycles per second. A modified form of apparatus suitable for use in practicing the process of the present invention is shown in Figures 6 through 9, this modified form of apparatus being particularly devised for creating vibrational waves in the treating fluid which are ultrasonic in frequency and which may be effected at from two-hundred-fifty cycles per second, or less, to approximately sixty-thousand cycles per second, it being preferable that the treating fluid has ultrasonic vibrational waves created therein at a frequency of approximately twenty-six thousand cycles per second.

With the primary exceptions of the outer walls of the main chamber being formed from rigid material and having electrical transducers provided with resonating or radiating surfaces thereon, the apparatus shown in Figures 6 through 9 may be substantially the same as the apparatus shown in Figures 1 through 5. The modified form of apparatus comprises a main chamber or tank 200 which is preferably substantially U-shaped, but need not necessarily be so. The apparatus shown in Figures 6 through 9 also includes a temperature controlling or auxiliary chamber 201, and a pair of front and rear sealing chambers 202, 202' all of which are quite similar to the respective chambers 10, 15, 35 and 35' of the first form of the apparatus.

The main fluid treatment chamber 200 is also adapted to contain a treating fluid F-1 and includes a substantially semi-circular, curved or arcuate bottom wall 205 which merges with a pair of opposed substantially rigid outer or front and rear side walls 206, 206'. Inner or front and rear auxiliary walls 207, 207' are spaced inwardly from and extend between respective outer side walls 208, 208' of the main tank or chamber 200 and define the auxiliary temperature controlling chamber (heating or cooling chamber) 201 therebetween, the temperature controlling chamber 201 being closed at its lower end by a plate 211 spaced above the bottom 205 of the main chamber 200. Since the main chamber 200 is substantially U-shaped, the two legs thereof form sub-chambers or compartments C, D. The plate 211 extends between and is connected to the inner wall members 207, 207' and temperature controlling chamber end wall members 210, 210' (Figure 8).

The main chamber 200 is carried by a suitable frame 214 shown in the form of a pair of laterally spaced end frame members 215, 215' which are of substantially U-shaped configuration for receiving the curved lower portion or bottom 205 of the main chamber 200. The frame members 215, 215' are bridged by stabilizing frame members or tie rods, 216 whose opposite ends are suitably secured to the end frame members 215, 215'.

Like the end walls of the main chamber 10 of the first form of the apparatus, the end walls 208, 208' of the chamber 200 are also substantially T-shaped and their upper portions serve as end walls to the sealing chambers 202, 202'. The upper portions of the front and rear side walls 206, 206' of the main chamber 200 also serve as the inner or proximal walls of the respective sealing chambers 202, 202'. The bottoms of the sealing cham-

bers 202, 202' are indicated at 220, 220' and the outer or distal walls of the sealing chambers 202, 202' are respectively designated at 221, 221'.

The lower portions of vertically disposed baffle plates 222, 222' terminate in spaced relationship above the bottoms 220, 220' of the respective sealing chambers 202, 202' and extend upwardly therefrom and preferably terminate above the level of the upper edges of the respective front and rear walls 221, 221'. Medial portions of the baffle plates 222, 222' have respective rests or projections 223, 223' thereon upon which front and rear edges of a cover plate or platform 224 normally rest. The cover plate 224 may be provided with one or more loop members or handles 226 thereon which may be engaged by a suitable lift mechanism, not shown, for raising the temperature controlling chamber 201 out of the main chamber 200 and to facilitate threading the web material W-1 therethrough, it being noted that the upper edges of the walls 207, 207', 208, 208' of the temperature controlling chamber 201 are suitably secured to and suspended from the cover plate 224.

The modified form of apparatus shown in Figures 6 through 9 is also provided with a pair of upper and lower feed rolls or ingress rolls 230, 231 and a pair of upper and lower egress or squeeze rolls 232, 233, all of which are preferably covered with a pliable or resilient material for the reason given with respect to rolls 50, 51, 65, 66 shown in Figure 4. The rolls 230, 231 and 232, 233 are mounted in respective pairs of bearing blocks or stands 234, 235 and may be mounted in these bearing standards 234, 235 in exactly the same manner in which the reduced ends of the rolls 50, 51, 65, 66 are mounted in the respective pairs of bearing blocks or standards 70, 70' and 71, 71'. Accordingly, a more detailed description of the manner in which the rolls 230, 231, 232, 233 are supported will not be given. It might be stated, however, that the bearing stands 234, 235 are suitably secured to corresponding end walls 208, 208' of the main chamber 200.

Since the egress rolls 232, 233 may serve as squeeze rolls, a suitable pan 236 is also preferably provided beneath the bottom squeeze roll 233 for returning any fluid which drains from the squeeze rolls 232, 233 into the front sealing chamber 202 through a suitable opening 237 provided in the front wall 221 of the front sealing chamber 202. It will be observed in Figure 9 that web guiding rolls 240 to 250 inclusive, are journaled in the opposed end walls 208, 208' of the main chamber 200 and are arranged in the identical manner to that in which the respective web guiding rolls 52 through 57 and 60 through 64 are arranged in Figure 4.

Thus, the web material W-1 passes between the driven upper and lower feed rolls 230, 231, then over the roll 240 and downwardly through the liquid seal formed in the sealing chamber 202', beneath baffle 222', then over the upper edge of the wall 206' of the main chamber 200, then downwardly between and through the compartment or sub-chamber D, partially around the relatively large roll 245 in the lower portion of the main chamber 200, then upwardly through the sub-chamber or compartment C, over the upper edge of the front wall 206 of the main chamber 200, then downwardly through the liquid seal, and beneath the baffle 222, then upwardly out of the liquid seal and over the roll 250 where it is withdrawn by the squeeze rolls or withdrawing rolls 232, 233. Guide rods 252, 252' may be provided in the sub-chambers C, D (Figure 9) between which the web W-1 passes in the manner described with respect to the guide rods 175, 175' in Figure 4. However, they may not be required when using ultrasonic waves in the processing fluid.

The rolls 230, 231 and 232, 233 are shown in Figure 6 as being driven in substantially the same manner in which the respective rolls 50, 51, 65, 66 are driven in Figure 5; that is, separate variable-speed drive units 255, 255' are

provided for the respective sets of top and bottom rolls 232, 233 and 230, 231, respectively. The variable-speed drive units 255, 255' may be suitably secured to the upper portion of the substantially T-shaped end wall 208, and each of them is provided with a suitable control 256 for controlling the output speed of the corresponding variable-speed drive unit.

The variable-speed drive units 255, 255' drive respective endless belts 260, 260' which engage respective pulleys 261, 261' fixed on corresponding reduced ends of the respective bottom rolls 233, 231. It will be observed in Figures 6 and 7 that corresponding reduced ends of the bottom rolls 231, 233 each has a gear 263 fixed thereon which meshes with a gear 264. The gears 264 are fixed on corresponding reduced ends of the respective top rolls 230, 232.

As is the case in the first form of the apparatus the treating fluid may be fed into the main chamber 200 by any suitable means and, since such means is embodied in Figure 9 identically in the manner in which it is illustrated in Figure 4, the corresponding parts of the treating-fluid feeding means shown in Figure 9 will bear the same reference characters as like parts shown in Figure 4 with a small letter "a" affixed thereto to avoid repetitive description. Of course, it is obvious that the upper portions of the pipe-lines 91a, 97a are communicatively connected to the respective liquid sealing chambers 202', 202.

A suitable fluid-level control means or pressure control means, shown schematically at 96a in Figure 9, may be provided in the upper portion of the main chamber 200 for maintaining the fluid F-1 at the proper level or under the proper negative or positive pressure, depending upon whether the fluid is in liquid or gaseous form. The fluid-level control apparatus 96a may be of the same type as the fluid-level control apparatus 96 shown in Figure 4 and a further description thereof is deemed unnecessary. A drain, embodied in a valve 100a is also provided at the lowermost portion of the arcuate bottom wall 205 of the main chamber 200 for draining the contents of the main chamber 200 for cleaning or other purposes when desired.

The temperature controlling chamber 201 may be maintained at the desired temperature, depending upon the character of the fluid and/or web material W-1 being processed, by any suitable means, such as that heretofore disclosed with respect to Figure 4. Accordingly, the elements of the temperature determining means shown in Figure 9 which correspond to elements shown in Figure 4 will bear the same reference characters with the small letter "a" affixed thereto, to avoid repetitive description.

As heretofore stated, the outer or front and rear walls 206, 206' of the main fluid chamber 200 are made from a rigid or substantially rigid material, such as sheet metal, and each of the compartments or sub-chambers C, D has high-frequency vibrational waves (ultrasonic) created therein which are in zones extending transversely or laterally of the path of travel of the web material W-1. In this instance, two successive zones of high-frequency vibrational waves are effected in each of the sub-chambers or compartments C, D of the main fluid chamber 200, which is preferred. However, a single lateral zone of high-frequency vibrations, or more than two successive zones of high-frequency vibrations may be effected in either or both of the sub-chambers C, D.

To this end, a pair of substantially parallel laterally extending or horizontally extending rows of closely spaced soundwave producing or resonating devices or transducers 270, 271 is provided on the front wall 206, and a similar pair of rows of transducers 270', 271' is provided on the rear wall 206', the transducers 271, 271' preferably being disposed in staggered relation to the transducers 270, 270' in the row thereabove in order that vibrational waves are created in the fluid F-1 throughout the entire width of the web material W-1 passing therethrough. The transducers 270, 271, 270', 271' may be of a type such as is

manufactured by Acoustica Associates, Inc., Glenwood Landing, Long Island, New York.

Each of the transducers 270, 271, 270', 271' may be of a type comprising a cup-like housing 272 having a flange 273 on its inner end which is penetrated by screws or other means 274 for securing the transducers to the corresponding walls of the main chamber 200. The transducers may each be of the magnetostriction or ceramic type which, by means of a coil 275 disposed within the corresponding housing 272, inaudibly vibrates a radiating or resonating face 276 on each of the transducers 270, 271, 270', 271'. Each of the transducers 270, 271, 270', 271' contains a coil 275, only one of which is shown schematically in Figure 9.

Alternating current of the desired frequency is supplied to the coil 275 of each of the transducers by any suitable means such as a generator 277. Each coil then causes a material contained within the corresponding housing 272 to vibrate through a rapid succession of changes in dimension, which vibrations are developed in the form of high-frequency sound vibrations at the radiating face 276 of each of the transducers 270, 271, 270', 271'. This results in cavitation bubbles being formed in the fluid F-1, which bubbles collapse and generate shock waves which can number several hundred thousand per second. In order that the high-frequency (ultrasonic) sound waves emanating from the radiating face 275 of each of the transducers 270, 271, 270', 271' are not restricted, the walls 206, 206' of the main chamber 200 each has openings or orifices 280 therein coinciding with the radiating face 275 of each of the transducers.

Due to the heat developed by the high-frequency alternating currents passing through each of the coils 275, a suitable circulating cooling medium, such as cold water, flows through each of the housings 272. To this end, each of the housings 272 of transducers 270, 271 has an outlet and an inlet conduit connected thereto which are respectively designated at 281, 282. Each of the housings 272 of transducers 270', 271' has respective outlet and inlet conduits 281', 282' connected thereto. The inlet and outlet conduits 281, 282 extending from the upper transducers 270, 270' are connected to respective common conduits 283, 284, 283', 284' and the inlet and outlet conduits 281, 282 extending from each of the lower transducers 271, 271' are connected to respective common conduits 285, 286, 285', 286'.

It will be observed in Figures 6, 7 and 8 that the substantially horizontal inlet conduits 283, 283' are connected with the conduits 285, 285' which are, in turn, connected to a common inlet pipe or conduit 287. All of the substantially horizontal outlet conduits 284, 286, 284', 286' are connected to a common outlet conduit or pipe 290 (Figure 6). Corresponding ends of the conduits 287, 290 are connected to a suitable circulating source of liquid coolant or water, shown schematically at 291 in Figure 7.

It might be stated that the material disposed within each of the housings 272, which is vibrated by the flow of alternating current of the desired frequency through the corresponding coil 275, may comprise piezoelectric quartz crystals, piezoelectric ceramics and certain iron and nickel alloys which can be magnetically made to change dimension and the radiating face 275 of each transducer may be in the form of a pliable disc made from Teflon or other suitable material or it may be in the form of a disc-shaped piston (resonator) projecting into the tank through the corresponding orifice or opening 280.

It is thus seen that each row of transducers 270, 271, 270', 271' creates a corresponding lateral zone of ultrasonic vibrations or pressure waves in the fluid F-1, the inner walls 207, 207' being sufficiently closely spaced to the respective outer walls 206, 206' so the waves of vibrations do not decrease materially in strength or intensity by the time they reach the opposite or inner wall 207, 207'. Of course, these waves are effected at such high frequency as to be inaudible and result, as here-

tofore stated, in cavitation. Cavitation not only creates high molecular velocity, but also "stretches" liquid, which can, for example, grind suspended particles to one one-hundred-fiftieth ($\frac{1}{150}$) micron in diameter, can disperse them uniformly in the fluid within the confined thickness of the fluid or effective field of the ultrasonic sources, and can "open up" pervious pliable materials, such as cloth.

It is thus seen that I have provided a novel method of processing continuous moving web materials as they pass through a treating fluid while creating a zone or zones of subsonic or ultrasonic vibrations in the treating fluid and in a lateral zone or lateral zones which preferably extend throughout the width of the web material being processed. It should be noted that the relatively narrow "thickness" of the fluid in each of the compartments in each form of apparatus disclosed herein minimizes the amount of fluid required to process the web material and, in the event that the web material need be heated, the amount of heating energy required to maintain the fluid at the proper temperature is minimized. It should be noted that it is only necessary to support some types of web material against movement with low-frequency or subsonic waves. The size of the waves diminish somewhat proportionally with increases in frequency so that it is normally unnecessary to support a web against movement of waves at ultrasonic frequencies.

In both forms of apparatus disclosed herein, it is to be understood that the distance between adjacent walls of the chamber between which the web passes is substantially proportionate to the amplitude of the vibrational waves created at the source to insure complete agitation of the fluid medium, whether it be liquid or gas, and thereby insure rapid and thorough penetration of the pervious web so the web can be processed at a much faster rate than has been possible with prior processes. In the claims, the term "amplitude" is used with respect to the source of vibration to indicate complete and thorough agitation of the fluid throughout its "thickness" at sonic and ultrasonic frequencies, and to formation of cavitation bubbles throughout thickness of a fluid in which ultrasonic vibrational waves are created. The distance from each source to the opposite wall should be within the effective range of the means producing the vibrational waves in the treating fluid.

In the drawings and specification there has been set forth a preferred embodiment of the invention and, although specific terms are employed, they are used in a generic and descriptive sense only and not for purposes of limitation, the scope of the invention being defined in the claims.

I claim:

1. Apparatus for the treating of web material including in combination a treatment chamber having first and second oppositely disposed walls adapted to contain a fluid therebetween and providing for passage of the web therethrough, means for continuously moving said web through the chamber, at least one of said walls being of a pliable material, and means for reciprocating a portion of said pliable material toward and away from the web at least throughout the plane of the width of the web for creating vibrational waves of predetermined frequency in the fluid.

2. A structure according to claim 1 wherein said pliable wall is provided with at least one additional means for reciprocating a portion thereof extending in substantially parallel spaced relationship to the first-named portion, and wherein said portions are moved relatively oppositely with each reciprocation thereof.

3. Apparatus for treating a continuously moving pervious web material comprising a sealed chamber having spaced substantially parallel oppositely disposed walls providing for the passage of the web therebetween, at least one of said walls being made from a pliable material, at least one laterally extending rigid member car-

ried by said pliable wall, and means for reciprocating said rigid member at predetermined sonic frequency of five to two-hundred-fifty cycles per second at such amplitude as to insure vibrational waves imparted to the fluid of substantially uniform intensity throughout the fluid between said walls.

4. A structure according to claim 3 wherein means are provided for maintaining the fluid between said walls at a predetermined temperature.

5. Apparatus for the fluid treatment of pervious web material comprising a sealed treatment chamber having oppositely disposed substantially parallel walls providing for the passage of the web therebetween in spaced substantially parallel relation thereto, at least one of said walls being made, at least in part, of a pliable material, a plurality of spaced substantially parallel rigid members secured to said pliable wall and extending substantially laterally of the plane of the path of travel of said web, and means for imparting reciprocatory movement to said rigid members toward and away from the web at a predetermined frequency and at sufficient amplitude to effect vibrational waves in the fluid which are of substantially uniform intensity throughout that portion of the fluid between each rigid member and the other of said walls.

6. A structure according to claim 5 wherein adjacent rigid members move relatively oppositely with each reciprocation thereof.

7. A structure according to claim 5 wherein said oppositely disposed walls are spaced one to six inches apart.

8. Apparatus for the fluid treatment of pervious web material comprising a treatment chamber having relatively closely spaced oppositely disposed substantially parallel walls providing for the passage of the web therebetween in spaced substantially parallel relation thereto and adapted to contain a fluid therebetween, at least one of said walls being made, at least in part, of a flexible material, a plurality of spaced substantially parallel rigid members carried by said flexible wall and extending substantially laterally of the plane of the path of travel of said web, and means for imparting reciprocatory movement to said rigid members toward and away from the web at a predetermined frequency and at sufficient amplitude to effect vibrational waves in the fluid which are of substantially uniform intensity throughout that portion of the fluid between each rigid member and the other of said walls.

9. A structure according to claim 8 wherein adjacent rigid members move relatively oppositely with each reciprocation thereof.

10. A structure according to claim 8 wherein said oppositely disposed walls are spaced from one to six inches apart.

11. Apparatus for the fluid treatment of a pervious web material comprising an upright substantially U-shaped sealed chamber for containing a treating fluid therein and having spaced substantially parallel oppositely disposed walls defining therebetween a substantially U-shaped passageway, means for continuously feeding the web into and withdrawing the web from said passageway while moving the web in substantially parallel spaced relationship between said oppositely disposed walls, means for heating said fluid at least one of said walls having a source of vibrational energy for creating vibrational waves in the fluid against the other of said walls, said source of vertically spaced vibrational energy comprising a plurality of substantially parallel rows of transducers extending substantially laterally of the corresponding wall with respect to the path of travel of the web, the transducers in each row having resonating faces arranged in closely spaced relationship, transducers in adjacent rows being disposed in staggered relationship so as to produce

vibrational waves throughout the plane of at least the width of the said web, and the amplitude of the vibrational waves created by said transducers being such relative to the distance between the transducers and the other of said walls that the waves are of substantially uniform intensity throughout the thickness of the fluid between said oppositely disposed walls.

12. Apparatus for the liquid treatment of web fabric comprising an upright substantially U-shaped chamber including closely spaced side walls forming a substantially U-shaped passageway for containing fluid therein, means for continuously feeding a web into one end of said passageway, means guiding said web through said passageway, means withdrawing said web from the other end of the passageway, means for feeding fluid into said passageway, means for heating said fluid, a pressure seal at each end of said passageway, vertically spaced vibrational wave producing means extending throughout a substantial portion of the width of at least one of said side walls and projecting vibrational waves at substantially right angles to the path of travel of the web, and said wave producing means having sufficient energy relative to the spacing of the walls so that the waves are of substantially uniform intensity throughout the fluid between the walls in the horizontal plane thereof.

13. A structure according to claim 12 wherein said wave-producing means comprises vertically spaced rows of transducers extending substantially laterally of the corresponding wall with respect to the path of travel of the web.

14. A structure according to claim 12 wherein said wave-producing means is in the form of at least one substantially parallel and laterally extending rigid member secured to said one of said walls and extending laterally with respect to the path of travel of the web, said one of said walls being made from a resilient material, and means for imparting inward and outward reciprocatory movements to said rigid member relative to the web.

15. A structure according to claim 12 wherein said wave-producing means is in the form of a plurality of substantially parallel and laterally extending rigid members secured to said one of said walls and extending substantially laterally with respect to the path of travel of the web, said one of said walls being made from a resilient material, and means for imparting inward and outward reciprocatory movement to each of said rigid members relative to the web.

16. Apparatus for the fluid treatment of material comprising a treatment chamber having relatively closely spaced oppositely disposed substantially parallel walls for containing a fluid therebetween and for receiving the material to be treated therebetween, at least one of said walls being made, at least in part, of a flexible material, a plurality of spaced substantially parallel rigid members carried by said flexible wall and extending substantially laterally of the material to be treated, and means for imparting reciprocatory movement to said rigid members toward and away from the material to be treated at a predetermined frequency and at sufficient amplitude to effect vibrational waves in the fluid which are of substantially uniform intensity throughout that portion of the fluid between each rigid member and the other of said walls.
